[57] CLAIM

The ornamental design for a headphone, as shown and
described.

DESCRIPTION

FIG. 1 is a rear and right-side perspective view of a
headphone, showing our new design;

FIG. 2 is a perspective view of an earpiece thereof,
shown on an enlarged scale;

FIG. 3 is a front elevational view thereof;

FIG. 4 is a rear elevational view thereof;

FIG. 5 is a right-side elevational view thereof, the left
side being a mirror image thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
